UNITED STATES PATENT OFFICE

2,508,839

AIR CONDITIONER

James F. Roe, Salt Lake City, Utah

Application June 8, 1948; Serial No. 31,671

1-Claim. (Cl. 261—92.)

1.

This invention comprises novel and useful improvements in air conditioners and more specifically pertains to a portable device for humidifying and circulating air for conditioning rooms and the like.

The principal object of this invention is to provide an apparatus for efficiently humidifying and moistening air and for circulating the same as desired.

A further object of the invention is to provide a device as set forth in the preceding object which shall be of portable construction, easily serviced, and which shall comprise as its air circulating medium a conventional type of electric fan.

An important feature of the invention resides in the provision of a device including an electric motor driven air fan and a humidifying wheel which is aligned with and rotated by the stream of air from the air fan.

A further feature of the invention envisions the construction of a portable humidifier as set forth in the preceding paragraph wherein the humidifying wheel is detachably mounted and journalled for rotation above and for immersion in a removable liquid or water tank which shall be removably housed in the casing enclosing the air fan.

Yet another important feature of the invention comprehends the provision of a novel and improved construction of humidifying wheel for more efficiently causing a dispersion of the water picked up by the wheel from the tank for commingling with the stream of air from the air fan.

And a final important feature of the invention to be specifically enumerated herein resides in the provision of an apparatus wherein a plurality of different shaped humidifying wheels may be readily employed therewith, wherein a simplified and inexpensive construction is provided for application to a conventional electric fan for adapting the same for humidifying and conditioning air, and wherein there is provided a lightweight, compact and inexpensive device for effectively moistening air in rooms and the like as desired.

These, together with various ancillary features and objects of the invention which will later become apparent as the following description proceeds, are attained by this device, a preferred embodiment of which has been illustrated by way of example only in the accompanying drawings, wherein:

Figure 1 is a fragmentary perspective view, parts being broken away, showing a preferred embodiment of the invention and in particular disclosing the mounting of the electric fan, the

2.

humidifying wheel, the liquid tank properly positioned within the housing of the device;

Figure 2 is a fragmentary elevational view of a portion of a preferred embodiment of humidifying wheel which may be employed with the invention;

Figure 3 is a fragmentary detailed view taken upon an enlarged scale substantially upon the plane of the section line 3—3 of Figure 2, showing the construction of the apertured humidifying wheel;

Figure 4 is a fragmentary elevational view, similar to Figure 2, but showing a modified construction of humidifying wheel; and

Figure 5 is a vertical longitudinal sectional view through the device of Figure 1, the end screens being removed, and showing the relative arrangement of the parts.

Referring now more specifically to the accompanying drawings, wherein like numerals indicate similar parts throughout the various views; the numeral 10 designates generally the preferred embodiment of the invention to be hereinafter described. It may be here stated that the prime requisite of this invention is to provide a device which may be incorporated with any conventional electric driven fan for adapting the same to supply moist and liquid conditioned air for improving the atmosphere of rooms and the like. Of course, it will be understood that other liquids as well as water may be used with the device, which admirably serves the purpose of impregnating air with various liquids, and circulating the thus moistened air, the stream of air from the electric fan serving both to more effectively commingle the liquid and the air as well as to cause rotation and hence operation of the moistening means.

The portable air conditioner 10 includes a supporting base 12 of any suitable construction, whether of a solid construction or of a skeleton or lattice-work construction as desired. Mounted upon the supporting base 12 is a housing indicated generally by the numeral 14, and including side and end walls, which housing is provided with a hinged, substantially semi-circular cover or closure 16, which is hinged longitudinally of one of the walls of the device as by a hinge 18. This cover, a portion only of which is shown in Figure 1, is intended to be secured in its closed position by means of any conventional type of fastener or locking device 20. As so far described, the housing may be of various sizes and shapes, but is preferably formed of lightweight sheet metal construction in the interest of lightness and inexpensiveness.

The end walls of the housing are provided with preferably substantially circular openings 22 and 24 which respectively constitute air inlet and conditioned air outlet openings, each of which is preferably closed as by a screen or grill 26 removably secured in any desired manner to the end walls and over these openings. Securely supported by the base 12, and preferably adjacent the air inlet opening 22, is a supporting bracket or standard 28, upon which are detachably secured as by a fastening strap 30, the electric motor 32 of any conventional electric fan, having a fan blade 34 thereon. As will be readily understood, the size of electric motor and fan blade to be incorporated in the device will be chosen in proportion to the size of the housing, and of the opening 22.

Indicated at 36 is any conventional means for supplying electric current to the motor 32 for operating the fan 34, and if desired the electric motor or the cable may comprise a rheostat for regulating the speed of the fan.

Suitably secured to the base 12 is a transversely extending, angle iron member 38 which constitutes a retaining means for a transversely disposed tray or tank 40, which is thus removably secured and positioned upon the base 12, any desired means being provided for releasably anchoring the tray or tank to the base. As shown best in Figure 5, the side walls of the tank 40 respectively engage the transverse retaining member 38, and the end of the housing containing the air outlet opening 24.

Upon the inner side walls of the tank 40, are secured as by rivets or bolts 42 the lower ends 44 of a pair of vertically disposed supporting standards. These standards preferably consist of strips of metal or the like, and are preferably resilient in their nature. From the lower extremities 44, each standard is provided with an inwardly and upwardly extending portion 46, whose upper ends are provided with parallel portions 48, whose extremities are turned inwardly and outwardly in parallelism to themselves as at 50 and are provided with apertures for detachably receiving therein a shaft 52 constituting an axle which is removably received in a tubular bushing 54 constituting a part of the hub portion 56 of a humidifying wheel.

Since the supporting standards are resilient, the upper ends may be readily but yieldingly pulled away from each other, whereby the axle 52 may be inserted or removed from the bearing apertures in the portions 50, it being understood that the unapertured portions 48 constitute means to maintain the axle in the bearings and consequently, the hub of the wheel in position.

As shown best in Figures 1 and 2, a plurality of radially extending sector-like vanes 58 are integrally or if desired, separately carried by the hub portion 56, and each of these vanes is given a pitch similar to that of a propeller blade, for a purpose which will later become apparent. Each of these sector-like vanes 58 is provided with a plurality of parallel slots 60, which extend in parallelism to the medial radius of each vane. As shown in the detailed view of Figure 3, the parallel slots are formed by bending one edge of each at an angle to the plane of the vane, to thereby provide parallel flanges 62 extending in parallelism substantially radially of the blade.

The wheel is so mounted upon the supporting standards that the lower vanes thereof are immersed in the liquid provided in the tank 40, whereby the flanges 62 and slots 60 pick up por-

tions of the liquid as the wheel is rotated, and as the individual vanes are rotated, the liquid thus elevated is distributed by gravity, and by centrifugal force radially along the slots 60 and the flanges 62, whereby the same substantially covers the area of the vanes, and whereby the air stream from the fan 34 flowing through the humidifying wheel will readily pick up and contact the moisture carried by the vanes and thereby be moisture laden.

It should be here noted that preferably the size of the wheel is such that the same is but slightly smaller than the fan 34, whereby the air blast from the latter will thoroughly disperse over the area of the wheel, pass through the interstices thereof and about the periphery thereof, for effective and efficient vaporization and humidifying action by the liquid in the tank 40.

The pitch of the vanes 58 is such that the wheel is slowly rotated by the air blast, the slowness of this rotation being attributed to the resistance of the liquid contained in the tank.

Preferably, the axle 52 is axially aligned with the axis of rotation of the fan, as will be readily understood by reference to Figure 5. Of course, in some instances it may be preferred to position the axis of rotation of the wheel at an angle to the axis of rotation of the fan, and further baffle means may be interposed between the same for the purpose of better diffusing the air, and even slowing down the rate of flow of the same, in order to create a more gentle flow through, around and over the apertures of the wheel.

It should be here noted that by opening the cover 16, the tank 40 may be removed as a unit with its humidifying wheel, in order to service the same, to interchange or remove the wheel and replace the same with other forms of wheels, as set forth hereinafter, or for servicing as desired, and similarly, the fan and motor may likewise be removed or replaced.

Alternatively, various other constructions of wheels may be employed. Thus, as shown in Figure 4, the hub portion 64 corresponding to the hub 56, and similarly mounted between the support standards, may be provided with a plurality of sectorial shaped vanes 66, which instead of the slots previously mentioned may consist of a plurality of apertures 68 to thus provide foraminous or reticulated vanes. Otherwise, the construction is identical with that previously set forth. Moreover, it should be further noted that the slots of the vanes need not be parallel, nor straight lines, but could consist of various curves, contours, configurations and dispositions for the purposes of more effectively distributing the liquid elevated over the surface of the fan for interspersing liquid in the air stream.

It is desired to here emphasize that the underlying principle of this invention resides in the ease and facility for removing, servicing or adjusting the humidifying wheel unit, removing or replacing the tank and the wheel unit, and for obtaining access to and servicing the fan. Further, it will be noted that the motor 32 of the fan by means of the strap 30, may be readily adjusted to move the same towards or from the wheel, to thereby further regulate the effectiveness of the driving relation between the fan and the wheel, and for this adjusting the speed of rotation of the wheel from the fixed speed of rotation of the fan. This latter function arises from the fact that neither the fan nor the wheel occupy the entire confines of the cross-sectional

area of the housing and that there is consequently some slippage of air both around the periphery of the fan and of the wheel, and inside the housing. By positioning the fan closer to the wheel, a greater proportion of the force of blast of the air fan will be employed to rotate the wheel.

It is especially to be noted that this device is inherently capable of delivering a cool dry air rather than air of high humidity, since the metal construction of the wheel will effect a condensation of moisture particles preventing a saturation of the air, whereas a moisture supplying element of fabric would not possess this function.

From the foregoing, the manner of constructing and operating the device and its manifold advantages will be readily understood and further explanation is believed to be unnecessary. However, since numerous modifications and changes will readily occur to those skilled in the art after a consideration of the foregoing specification and accompanying drawings, it is not intended to limit the invention to the exact construction and arrangement shown and described, but all suitable modifications and equivalents may be resorted to falling within the scope of the appended claim.

Having described the invention what is claimed as new is:

In a portable air conditioner having a base, a housing thereon having screened air inlet and outlet openings, a motor driven fan in said hous-

ing; a humidifying device including a water tank within said housing extending transverse said base, a pair of standards carried by the sides of said tank, a humidifying wheel having an axle rotatably journaled in said standards and aligned with the axis of rotation of said fan, said wheel having a plurality of propeller shaped sectorial perforated vanes, said wheel being positioned for immersing said vanes in the water in said tank during rotation, the perforations on said vanes comprising substantially radially extending slots with flanged edges for distributing water dipped from said tank radially throughout the entire area of each vane for penetration by the air stream from said fan, the pitch of said vanes causing rotation of said wheel by said air stream, said standards having their upper ends turned inwardly toward each other and downwardly, said upper ends being parallel and having aligned bearings for receiving said axle, the standards being flexible and the unbent portions forming bearing closures for retaining said axles therein.
